UNITED STATES PATENT OFFICE

2,213,862

OIL BURNER

David J. Howard, Chicago, Ill., assignor to Quaker Manufacturing Company, Chicago, Ill., a corporation of Illinois

Application November 18, 1938, Serial No. 241,171

9 Claims. (Cl. 158—91)

My invention relates to an improvement in a method of and means for controlling the air supply to pot type liquid hydrocarbon burners.

One purpose is the provision of means for obtaining a differential cooling effect at low or natural draft and at high draft.

Another purpose is the provision of means for supplying air under pressure to a pot type burner whereby, as the air pressure or air flow increases at high fire, an excess cooling effect on the pot is prevented.

Another purpose is the provision of means for by-passing air whereby as the pressure is increased about the pot, a substantial proportion of the additional air supplied flows to the general area of the upper air inlet or inlets without having a cooling effect upon other parts of the pot.

Another purpose is the prevention of capacity loss and flame pulsation which would otherwise be caused by the cooling effect of an increased air supply or air pressure.

Other objects will appear from time to time in the course of the specification and claims.

I illustrate my invention more or less diagrammatically in the accompanying drawing wherein:

Fig. 1 is an elevation partly in vertical section; and

Fig. 2 is a vertical section on an enlarged scale of a portion of the structure which is shown in Fig. 1.

Like parts are indicated by like characters throughout the specification and drawing.

Referring to the drawing, 1 indicates a mixing and combustion pot having a bottom 2 preferably of thin sheet metal, a plurality of air inlets 3, and an upper row of air inlets 4. 5 is a top baffle which may if desired partially close the open top of the pot, the mixture and flame being thereby restricted to the central opening 6. 7 is an additional baffle which may, if desired, be located in a lower portion of the pot at various levels. It may be selectively positioned upon any one of a plurality of sets of studs or inward projections 8, 8a and 8b, shown extending inwardly into the interior of the pot 1 at different levels.

10 is a closed exterior housing connected to the pot 1 as by the top partition 11. The details may be varied but I illustrate the top partition 11 as welded to an outwardly extending flange 12 of the pot wall member 1. The member 11 may include a downwardly extending flange 13 which may be removably secured as by screws to the top of the closed housing member 10. The member 10 has a closed bottom 14.

15 indicates an air inlet duct in communica-

tion with the interior of the housing 10. At its outer end, the duct 15 is in communication with the air outlet member 16 of the fan housing 17. Any suitable fan blade structure 18 may be rotatably mounted therewithin and may be actuated by any suitable motor, not herein shown in detail.

19 is a liquid fuel supply duct terminating as at 20 in an inlet member in communication with the bottom member 2 of the pot. 21, 22 are any suitable supports or pedestals, the details of which do not of themselves form part of the present invention. The duct 19 extends to any suitable source of supply of a liquid hydrocarbon and any suitable means may be employed, not herein shown, for varying the flow of the liquid hydrocarbon in order that a controlled volume of liquid hydrocarbon may be delivered to the bottom member 2 of the pot.

It will be understood that any suitable control means are employed whereby the fan member 18 may be actuated or may be maintained inactive at the option of the user or upon the employment of thermostatic controls which are conventional in the art. It will be understood further that any suitable means may be employed, not herein shown in detail, for permitting a natural draft of air to flow inwardly along the duct 15 to the interior of the housing 10 when the fan 18 is not being actuated. It will be understood that air may be supplied to the apertures 3 or 4 either by natural draft or by the operation of the fan, whereby a substantial variation in air supply is maintained, depending upon the operator's need for heat or the actuation of the thermostatic controls.

In a furnace of the present type, it has been customary to deliver air about the bottom member 2 for passage upwardly around the exterior of the pot to the air inlet apertures 3 and 4. This has the advantage of cooling the bottom of the pot and preventing overheating and burning out of the thin sheet metal parts often employed. It is disadvantageous, however, since when the air supply is increased, an increasing volume of air flows across the bottom of the member 2 in order to support the higher fire, this increased air flow causing an increased cooling effect on the bottom 2. This cooling effect not only tends to decrease the capacity of the burner but causes an uneven pulsating flame.

I therefore find it desirable to provide means, effective primarily during fan operation or at high natural draft, for by-passing a portion of the increased air supply for high fire, whereby this

55 55

increase in the air supply may be obtained without a corresponding increase in the cooling effect of the necessary increased air flow.

I find as a practical solution of this problem 5 the employment of an intermediate shell or housing member 30 which is herein shown as having an upper flange 31 which may be welded or otherwise secured to the bottom of the partition member 11. It is shown as having a bottom 32, with 10 a central air inlet aperture 33 which may for convenience be lined with the central portion of the exterior of the bottom member 2. It is also provided with a plurality of air inlets 34, preferably arranged in an upper portion of the member 30. These air inlets, which of course may be 15 widely varied in size, shape, number and location, are preferably generally aligned with or located in general opposition to the upper air inlets 4 or the upper air inlet zone at the top of the pot 20 member 1.

The total cross sectional area of the apertures 34 is substantially less than the area of the bottom aperture 33 or the area of the annular passage leading from opening 33 between the bottom 25 walls 2 and 32. Thus at natural draft, or in general at low draft, the air which flows inwardly along the duct 15 will for the most part flow directly upwardly through the aperture 33 and against the bottom of the member 2, to have its 30 appropriate cooling effect, and will flow upwardly about the pot to supply the air inlets 3 and eventually the upper air inlets 4.

It will be understood that at very low flame, or 35 at pilot flame, the apertures below the baffle 1 will provide the primary air supply, and the apertures above the baffle 1 will fall in the category of secondary apertures. At this low-burning stage, there is an insufficient air supply to cause 40 any undesired or undesirable cooling of the bottom 2.

When the operator turns up the fire, whether 45 by direct manual operation or by the interposition of any suitable thermostatic control means, the fuel supply along the duct 19 may be increased and air is delivered under pressure from 50 the fan 18 along the duct 15. As soon as any substantial air pressure builds up in the space within the housing 10, air will by-pass in increasing volume through the apertures 34. The flow 55 of air upwardly through the aperture 33 will not increase sufficiently to have any unfavorable cooling effect on the bottom 2. An increasing proportion of the air supply will pass through the apertures 34 directly to the upper zone, where the increased supply is necessary.

It will be understood that at high fire the secondary air flows through the apertures 4, the 60 apertures 3 providing the primary air supply for the preliminary mixture. Thus at high fire, when the secondary air supply is delivered through the top row of apertures 4, the greater portion of the additional air necessary for this secondary air supply flows upwardly between the housing 10 and the intermediate member 30, and through 65 the apertures 34, having no cooling effect whatsoever on the bottom of the pot 2, and avoiding any tendency to reduce, by such cooling, the capacity of the burner.

There is thus a differential effect obtained in 70 response to an increase in draft or air pressure, and much of the increased supply of air necessary for a higher fire is supplied directly to the secondary zone through the apertures 34, there being little increase of air flow across the exterior of the bottom 2. Thus I am able to increase 75

the air supply for high flame without any substantial increase in the cooling effect of the air on the bottom 2. This increases the capacity of the burner and prevents that pulsation of flame which takes place when there is a contest between the cooling effect of the inflowing air on the bottom 2 and the heating effect of the increased fire above the bottom 2.

A further function of the shield or intermediate member 30, in connection with the structure 10 with which it is employed, is in preventing undue heating of the air supply which flows through the apertures 34. I find by experience that there is an actual increase in capacity obtained by supplying relatively cool air to the apertures 4, at 15 high flame, when the apertures 4 are serving as the source of secondary air for the high flame.

If the air is unduly heated, it expands and the effective amount of oxygen per cubic unit of the inflowing heated air is correspondingly reduced. 20 Hence, I am actually able to obtain a greater oxygen supply per cubic unit of inflowing air by keeping the air relatively cool.

The wall 30, in connection with the insulating and cooling effect of the upward current of air 25 between the pot 1 and the intermediate member 30, is effective to keep the air between the members 10 and 30 at a relatively low temperature, with a consequent increase in effective oxygen content per cubic unit.

It will be realized that whereas I have described and shown an improved structure and method, nevertheless many changes may be made in the size, shape, number and disposition of parts and in the details and steps of such method 35 without departing from the spirit of my invention. I therefore wish my description and drawing to be taken as in a broad sense illustrative and diagrammatic, rather than as limiting me to my precise structure.

I claim:

1. In combination, in a pot type burner, a pot having a bottom and a circumferential side wall, said side wall having air inlet means in a lower portion thereof and a plurality of air apertures in an upper portion thereof, means for supplying combustion air under pressure to said burner, including means for delivering air across the exterior of the bottom of said pot for supplying air to said apertures, said air being effective to cool said pot bottom, and means for by-passing part of the air from the supply along a path separated from the bottom of said pot, to the general area of the upper air apertures, whereby an additional supply of air may be provided without a corresponding increase in the flow of air across the pot bottom, said means including a shield interposed between the air supply and the exterior of said pot, said shield being apertured in line with the bottom of said pot and in line with an upper portion of said pot.

2. In combination, in a pot type burner, a pot having a bottom and a circumferential side wall, said side wall having air inlet means in a lower portion thereof and a plurality of air apertures in an upper portion thereof, means for supplying combustion air under pressure to said burner, including means for delivering air across the exterior of the bottom of said pot for supplying air to said apertures, said air being effective to cool said pot bottom, and means for by-passing part of the air from the supply along a path separated from the bottom of said pot, to the general area of the upper air apertures, whereby an additional supply of air may be provided without a corre- 75

- sponding increase in the flow of air across the pot bottom, said means including a shield interposed between the air supply and the exterior of said pot, said shield being apertured in line with the bottom of said pot and in line with an upper portion of said pot, the apertured area of the bottom of the shield substantially exceeding the apertured area of the top portion of the shield. 5
3. In a burner for liquid hydrocarbons, an inner pot member having a circumferential wall, a plurality of air apertures in the lower portion of the wall, a plurality of air apertures in the upper portion of the wall, an outer housing surrounding said pot, means for supplying air to said outer housing, and shielding means intermediate said inner pot and outer housing, said means being apertured to direct air from said housing against the bottom of said inner pot member and having additional apertures for supplying air from 10 the housing to the pot alined with an upper portion of said inner pot. 15
4. In a burner for liquid hydrocarbons, an inner pot member having a circumferential wall, a plurality of air apertures in the lower portion of the wall, a plurality of air apertures in the upper portion of the wall, an outer housing surrounding said pot, means for supplying air to said outer housing, and shielding means intermediate said inner pot and outer housing, said means being apertured to direct air against the bottom of said inner pot member and having additional apertures alined with an upper portion of said inner pot, the apertured area of said upper portion of the shield being less than the apertured area of 20 the lower portion of the shield. 25
5. In a burner for liquid hydrocarbons, an inner pot member having a multiple apertured circumferential side wall and a closed bottom, a closed outer housing surrounding the sides and bottom of said pot, means for supplying air under selected pressure to said outer housing, and an intermediate shell interposed between said inner pot and outer housing, said intermediate shell having an opening in its bottom in line with the bottom of said pot member, and being additionally apertured in its upper side portion in line with an upper portion of said pot member. 30
6. In a burner for liquid hydrocarbons, an inner pot member having a multiple apertured circumferential side wall and a closed bottom, a closed outer housing surrounding the sides and bottom of said pot, means for supplying air under selected pressure to said outer housing, and an intermediate shell interposed between said inner pot and outer housing, said intermediate shell being apertured in line with the bottom of said 35
- pot member, and being additionally apertured in line with an upper portion of said pot member, the bottom aperture area of said intermediate means exceeding the upper aperture area. 40
7. In combination, in a pot type burner, a pot having a bottom and a circumferential side wall, said side wall having a plurality of air inlet apertures located at various levels therein, means for delivering air across the exterior of the bottom of said pot to the lower of said air inlet apertures, and for delivering air to the upper of said apertures at a relatively low temperature by shielding the air so delivered, whereby the heating effect thereon of the proximity of the pot is substantially reduced, said means including an outer housing surrounding the sides and bottom of the pot, means for delivering air to said outer housing, and an intermediate shield between said outer housing and pot, said shield being apertured in line with the bottom of the pot and in 20 general alinement with the upper air inlet apertures. 45
8. In a burner for liquid hydrocarbons, an inner pot member having a closed bottom and a substantially cylindrical side wall provided with a plurality of air apertures including a circumferential series adjacent the upper end of the pot, an outer housing enclosing the sides and bottom of the pot, means for delivering air under selected pressure into the housing, and means positioned between the housing and pot for directing a portion of this air in contact with the bottom of the pot before it passes through the apertures, and for positively shielding another portion of this air from engagement with the lower portion of the pot and by-passing this air direct to the upper series of apertures. 50
9. In a burner for liquid hydrocarbons, an inner pot member having a closed bottom and a substantially cylindrical side wall provided with a plurality of air apertures including a circumferential series adjacent the upper end of the pot, an outer housing enclosing the sides and bottom of the pot, an intermediate shell positioned in the space between the housing and pot and dividing this space into an outer space between the housing and shell, and an inner space between the shell and pot, means for delivering air under selected pressure into the said outer space, the shell being closed except for an opening in its bottom and apertures adjacent its upper end through which air passes from the outer space to the inner space and thence through the apertures in the pot wall. 55
